UNITED STATES PATENT OFFICE.

GEORGE F. SHAVER, OF NEW YORK, N. Y.

MECHANICAL-TELEPHONE EXCHANGE.

SPECIFICATION forming part of Letters Patent No. 354,942, dated December 28, 1886.

Application filed January 25, 1886. Serial No. 189,619. (No model.)

To all whom it may concern:

Be it known that I, GEORGE F. SHAVER, a citizen of the United States, residing at New York, in the county of New York and State 5 of New York, having invented certain new and useful Improvements in Mechanical-Telephone Exchanges, of which the following is a specification, reference being had therein to the accompanying drawings, in which--

10 Figure 1 represents in perspective, and partly in section, a side view of the central office of said exchange. Fig. 2 represents a plan view of said central office. Fig. 3 represents the operator's hand-telephone.

15 The invention relates to improvements in mechanical-telephone exchanges from which radiate a number of wires for telephonic communication, and wherein any two wires may be connected, so that communication may be 20 made from the farther end of any one of said radiating wires to the farther end of any other.

25 The object of my invention is, first, to provide an easy means of making such connections; second, means for keeping the wires 30 taut when connected; third, providing means whereby many pairs of wires may be connected at the same time without interference; fourth, providing means whereby the operator 35 may easily connect his telephone with any line-wire and tighten the wire. I attain these objects with the mechanism illustrated in the accompanying drawings hereinbefore mentioned, in which similar letters refer to similar parts throughout the several views.

35 The wires converging to the central station are marked X X, and they are preferably arranged at the points where they pass through the walls of the building with a diaphragm, H, and button I, as shown in my Letters Patent 40 No. 298,243, granted May 6, 1884. From these diaphragms they converge to the connecting apparatus.

45 Each line-wire within the room of the central office has a branch, y, for connection with the operator, and each branch y has a signal-wire, z, for electric connection.

50 At a central position in the office is erected a frame, B D, preferably of circular form, upon suitable supports, C C, and within this frame 55 the operator stands. In the lower tier, D, of this frame are placed the connections of the

branch lines y and signal-wires z. Each signal-wire may be connected with a battery, E, for the sending of call-signals from the central office to line; and it also has its separate receiving relay or magnet, F, by which the central operator is called, and I prefer to have these relays each connected with a numbered drop-signal, as illustrated in Fig. 1, by any well-known appliance. Each branch wire y passes 60 through the aperture G in said lower tier, D, of the frame B D, and terminates upon the frame in a hook, J, with a suitable stop enlargement or button to keep it in place, and to this hook J the operator connects his hand mechanical 65 telephone K upon receiving an electric signal, in order to ascertain with what wire connection is desired. This hand-telephone K is shown in Fig. 3, and in order to keep the branch wire y taut the frame of telephone K 70 is attached to a handle, L, which has a projecting hook, M, which may be attached upon the fulcrum-rod N opposite any hook J; and thus the operator by pressing the handle L away from him will tighten the branch wire y 75 sufficiently for acoustic purposes. The rod N should be attached within and slightly below the frame D, and the arc of its circle should be concentric with that of D when the frame is circular; or when the frame is made 80 of one or more straight sides, then the rod should be correspondingly framed.

Between the top and bottom frames, B D, are any suitable number of uprights, O O, between which slide up and down, as far as the 85 frame B D will allow, the movable supports or frames P P. Each of these supports or frames has a central aperture, through which passes a line-wire, X, said line-wire terminating in a hook, Q, and a button, and I prefer to have 90 each frame contain a central hollow space and diaphragm, as shown at R. By connecting together any two of these hooks Q with a supplemental connecting-wire, S or S', and drawing them taut by means of a hanger, T, it is 95 evident that telephonic communication can be made between any two distant stations, and as the frames P may be placed at any convenient height it is also evident that each pair of wires may be connected at a different height 100 from any other pair, thus preventing interference of the wires. These hooks Q are also con-

venient for attaching the operator's hand-telephone, as shown at Z, Fig. 1, in which case the wire may be drawn taut by hand.

The method of tightening the wires is as follows: In the center of the circular frame B D is placed a spiral rod, U, rigidly supported in any suitable manner and capable of supporting at any point a tightening device, consisting, preferably, of a bent lever, V, which may be hooked over it, as shown in Fig. 1, the fulcrum of said lever being at the point where it is hooked over the rod. Now, if the hanger T be attached to the upper short arm of this bent lever, it is evident that by depressing the long arm thereof the connecting-wire S may be tightened to any desired extent, and by means of the cord W, passing over the end of the bent lever and secured to a cleat below it, the proper tension may be preserved. Numerous pairs of wires may thus be connected at the same time and kept taut by adjusting the frames of each pair at a different height and applying a separate lever, V, at a corresponding height upon the spiral rod U. Instead of a round rod, U, or in addition to the same, there may be used a stiff spiral band, X, Fig. 1, perforated at convenient points, and through such perforations the hanger Y and connecting-wire S' may be attached by means of a hook, as indicated, and the proper tension may then be given to the connecting-wire S' by a tightening device consisting of a cord and pulleys, Z', the cord being secured to a cleat below. The ends of the wires x may have, in addition to the hook Q, a separate slotted end piece, Q', Fig. 2, with a deep slot capable of holding a resilient or spring connecting-wire, S'', so that when a connection is desired between two line-wires they may be connected by inserting into the slots the spring-wire S'', which will then be held in place by its own resilient tension, and will convey vibrations by the same tension from one line to the other. I do not, however, make specific claim to this construction in this application.

What I claim, and desire to secure by Letters Patent, is—

1. In a mechanical-telephone exchange, a

spiral support, in combination with a supplementary wire connecting two line-wires and secured to a hanger, and with a tightening device interposed between said spiral support and hanger, substantially as set forth. 50

2. In a mechanical-telephone exchange, the combination of movable supports for the ends of the line-wires with a detachable supplemental wire connecting any two of said line-wires, substantially as described. 55

3. In a mechanical-telephone exchange, the combination of movable supports for the ends of the line-wires with a supplemental wire connecting any two of said line-wires, and a tightening device, substantially as described. 60

4. In a mechanical-telephone exchange, the combination of a spiral support with movable supports for the ends of the line-wires, a detachable supplemental wire connecting said ends, and a suitable tightening device, substantially as described. 65

5. In a mechanical-telephone exchange, the combination of a frame, B D, containing a series of sliding supports for the ends of the wires, and a detachable connecting-wire, substantially as described. 70

6. In a mechanical-telephone exchange, the wire x and the supplemental wire y, each terminating within the exchange in a hook or equivalent connecting device, in combination with a movable hand-telephone having a corresponding connecting device, substantially as described. 75

7. In a mechanical-telephone exchange, in combination with the fulcrum-rod N and a series of converging wires, each terminating in a hook or equivalent connecting device adjacent to said rod, the hand-telephone K, with means of attachment to any one such connecting device, and mounted on a lever possessing means of attachment upon any part of said rod as a fulcrum, substantially as described. 85

In testimony whereof I affix my signature, in presence of two witnesses, this 23d day of January, 1886.

GEORGE F. SHAVER.
